COAT CONSTRUCTION

Jerome Giuseffi, Cincinnati, Ohio, assignor to The Goodall Worsted Company, Sanford, Maine, a corporation of Maine

Application October 18, 1940, Serial No. 361,762

5 Claims. (Cl. 2—268)

This invention relates to the construction of skeleton lined coats and is particularly concerned with improvements in the formation of the shoulder portions of such coats.

An object of the invention is to provide a coat in which the yoke and forepart lining are of single thickness only and unattached to the shoulder portions of the body of the coat, that is, "the cloth."

Another object is to provide such a construction in which the shoulder pad is attached to the yoke and forepart lining, at the shoulder, and covered on its under side, beneath the yoke, by a piece of finish material attached to the yoke.

Another object is to provide a shoulder construction of the kind indicated which eliminates wrinkling and undesirable bunching of the shoulder-forming parts of the coat.

Another object is to provide means of this kind which permit alterations on adjacent portions of the coat body, particularly the shoulder, without disturbing the lining materials and shoulder padding and adjacent parts.

These and other objects are attained by the means described herein and illustrated in the accompanying drawing, in which:

Fig. 1 is a side view of a coat embodying the present invention, with parts of the coat omitted.

Fig. 2 is a view of one side of a coat of this invention, turned inside out, and with parts of the coat omitted.

Fig. 3 is an enlarged cross-sectional view on the line 3—3 of Fig. 1.

Fig. 4 is an enlarged cross-sectional view on line 4—4 of Fig. 1.

Fig. 5 is a cross-sectional detail showing an edge portion of the positioned pad involved herein.

The shoulder construction in coats, as they have ordinarily been made heretofore, involves a number of undesirable features and difficulties. These difficulties are particularly apparent when alterations on a coat, especially the shoulder portion, become necessary. Under present practice, in the formation of skeleton lined coats comprising yoke and forepart lining, these two parts have their adjacent edges stitched together and connected with the shoulder seam of the coat body, that is, of the cloth, as the main material of the coat is called. Consequently, upon alteration of the shoulder of a coat involving the opening of the shoulder seam, the yoke and forepart lining connections are likewise necessarily opened and the shoulder pad exposed and

displaced, or at least disarranged. In short, the shoulder alteration heretofore has been a complicated and time-consuming matter.

The older shoulder construction likewise involves the use of a double thickness yoke. In other words, the exposed portion of the yoke is, in turn, provided with a lining and these two parts are stitched together along the edges of the yoke forming an enclosure for the usual shoulder pad. The latter, however, has no proper kind of support within the constituent parts of the yoke, with the result that the pad "sheds," that is, fragments thereof dropdown into the closed edge portions of the yoke forming an undesirable and unsightly enlargement along this edge. In addition to this, the double thickness yoke becomes wrinkled and bunched with usage and after repeated cleaning and pressing operations.

These and other difficulties, which are well known in the field, have been eliminated by the present invention which provides, briefly, for a yoke and forepart lining of single thickness having their adjacent edges at the shoulder joined together but unconnected to the cloth or coat body whereby the latter is alterable along the shoulder seam without disturbance to the adjacent lining parts. The shoulder pad is attached to the under side of the yoke and, in the usual way, to the sleeve-head, and the under side of the pad, in turn, is covered by a piece of finish material attached to the yoke and also to the sleeve-head and forming, as it were, a supporting pocket for the otherwise exposed portion of the shoulder pad under the yoke.

In greater detail and with reference to the drawing:

Figs. 1 and 2 show a coat 10 comprising the usual main features, including the sleeve 11, the front section 12, and the back section 13 joined along a shoulder seam 14.

Fig. 2 shows the coat of this invention as provided with a yoke 15 and forepart lining 16 extending inwardly of the coat from the seam 17 which joins the forepart lining and the inner front portion 18 of the cloth or coat body.

The yoke 15 and forepart lining 16 are of single thickness and joined at the shoulder along the line 19 but unconnected to the shoulder seam 14, as has heretofore been the common practice. The upper portion of the yoke may be connected to the collar of the coat, as at 20, and the lower edge of the yoke adjacent the sleeve, as well as the adjacent edge portions of the forepart lining, are connected to the sleeve-head stitching of the coat around the armhole 21.

A shoulder pad 22, provided with the usual pad covers 23 and 24, is positioned beneath the forepart lining and the yoke, at the shoulder. The lower edge of the pad may be engaged by the sleeve connections, as at 25 (Fig. 3).

The portion of the shoulder pad beneath the yoke 15, in accordance with this invention, is covered by a piece 26 of finish material, which may have the same general outline as the associated portion of the shoulder pad but of somewhat larger dimensions. The piece 26, along with the adjacent edge portion of the shoulder pad, are connected by stitching 27 to the yoke 15. The inner edge of the finish piece 26 is indicated at 28 (Fig. 4). The lower edge of the finish piece 26, as seen in Fig. 3, may be connected, as at 29, with the same stitching that engages the upper end of the sleeve lining.

It will be seen in Fig. 4 that the usual interlining or "canvas" 30, provided in the foreparts of the coat, may overlie the under side of the shoulder pad 22 and may be connected, as at 31, with the edge 28 of the finish piece 26.

By the construction thus described, the yoke and the forepart lining adjacent the shoulder, as well as the shoulder pad and its finish cover, are all independent of the shoulder of the coat body, that is, of the front and rear parts 12 and 13 so that the seam 14 may be ripped for alteration of the shoulder or for any other necessary purposes, without in any way disturbing the underlying construction and parts.

Modifications suggest themselves upon consideration of the means herein disclosed but these are believed to be comprised within the spirit and scope of the invention.

What is claimed is:

1. A coat of the skeleton-lined type formed with a front and rear section joined along a shoulder seam lining material attached to the shoulder portion of the coat only at the collar and sleeve head, and a shoulder pad attached to the under side of said lining material and to the

shoulder portion of the coat only at the sleeve head.

2. The combination in a skeleton-lined coat, of a single thickness yoke and forepart lining joined at their meeting edges and unattached to the coat shoulder, a shoulder pad positioned beneath the yoke and lining, and a finish piece overlying the under side of the pad beneath the yoke and stitched only to the yoke and to the sleeve head.

3. The combination in a skeleton-lined coat, of a single thickness yoke and forepart lining joined at their meeting edges and unattached to the coat shoulder, a shoulder pad positioned beneath the yoke and lining, a finish piece overlying the under side of the pad beneath the yoke and stitching joining an edge of the pad and of said piece to the yoke.

4. A coat comprising a body having a front and a rear section connected by a shoulder seam, sleeves on the body, and a yoke and a forepart lining in the body joined adjacent said shoulder seam and unconnected therewith, said yoke having its upper edge portion only attached to said body, whereby said shoulder seam is rendered accessible beneath the yoke and forepart lining and may be ripped for alterations without disturbance to or interference with other portions of the coat adjacent thereto.

5. A coat comprising a body having front and rear section connected by a shoulder seam, sleeves on the body, a yoke and a forepart lining in the body joined adjacent said shoulder seam and unconnected therewith, said yoke having its upper edge portion only attached to said body, and a shoulder pad disposed on the forepart lining and yoke and attached only to the yoke and to the sleeve head, whereby said shoulder seam is rendered accessible beneath the yoke and forepart lining and may be ripped for alterations without disturbance to or interference with other portions of the coat adjacent thereto.

JEROME GIUSEFFI.
